UNITED STATES PATENT OFFICE.

THOMAS JACKSON, OF LONDON, ENGLAND, ASSIGNOR TO HIMSELF, AND ALLAN RAMSAY, OF CHESHAM, ENGLAND.

MECHANISM FOR PRODUCING GAS-LIGHTED FLASH-SIGNS.

1,073,420.

Specification of Letters Patent. Patented Sept. 16, 1913.

Application filed December 16, 1911. Serial No. 666,308.

To all whom it may concern:

Be it known that I, THOMAS JACKSON, subject of the King of Great Britain and Ireland, residing at 7 Milton Court road, 5 New Cross, London, S. E., England, have invented new and useful Improvements in and Relating to Mechanism for Producing Gas-Lighted Flash-Signs and the Like for Advertising Purposes, of which the following 10 is a specification.

This invention relates to improvements in mechanism for producing gas lighted flash signs and the like for advertising purposes and has for its object the provision of means 15 whereby the motive power of the gas is not only utilized to work the mechanism for producing an intermittent supply of gas as an illuminating agent but is in addition caused to provide the motive power by which the 20 lighted flash sign is moved.

My invention therefore consists in the combination of a gas driven intermittent control apparatus with a revolving lantern or support carrying advertising matter and 25 means by which the intermittent motion is transmitted from the gas control mechanism to the lantern or support carrying the advertisement.

One way of carrying the invention into 30 effect is by utilizing the lantern control mechanism operated by the gas used in the burner such as is described in the specification of U. S. A. Letters Patent No. 1009313 and connecting to any reciprocating part of 35 said apparatus a connecting mechanism which is adapted to give an intermittent rotation to the lantern or support carrying the advertisements.

In order that the invention may be the 40 better understood I will now proceed to describe the same in relation to the accompanying drawings, reference being had to the letters and figures marked thereon.

Like letters refer to like parts in the various figures, in which:—

Figure 1 is a view of the complete appara-

tus with my invention applied thereto. Fig. 2 is a plan of the ratchet wheel, the operating lever and pawl and the retaining pawl.

The flash light device *a* is similar to that 50 described in the specification of U. S. A. Letters Patent No. 1009313 and is given only as an example of a motor mechanism. The lantern *b* is pivotally mounted preferably on an anti-friction bearing *c* upon the gas 55 standard *d*. The lower part of the lantern fixedly carries a ratchet wheel *e* with which engages a retaining pawl *f* mounted on the standard *d* to prevent backward motion and an operating spring pawl *g* mounted on the 60 end of the bell crank *h*. The lever *i* of the mechanism *a* is connected to the bell crank *h* by a connecting rod *j* and a series of holes *k* are provided in both bell crank and lever to vary the leverage and the consequent motion 65 therefrom. As the mechanism *a* is operated by the gas the lantern is revolved thereby by a step by step motion and the revolution will continue so long as the gas is being used.

Having thus fully described my invention, 70 I claim as new and desire to secure by Letters Patent:—

A mechanically operated gas flash light device consisting of in combination, a motive mechanism adapted to be intermittently 75 actuated by the gas pressure of supply, a lighting burner supplied by gas from the intermittent exhaust of the said motive mechanism, a revoluble lantern adapted to carry advertising matter or the like and 80 connecting means for transmitting the intermittent motion of the said motive mechanism to the said lantern, substantially as described.

In testimony whereof I have signed my 85 name to this specification in the presence of two subscribing witnesses.

THOMAS JACKSON.
